(57) **CLAIM**

The ornamental design for a panel strip bracket, as shown and described.

DESCRIPTION

FIG. 1 is a front view of a panel strip bracket;

FIG. 2 is a bottom side view thereof;

FIG. 3 is a top side view thereof;

FIG. 4 is a right side view thereof;

FIG. 5 is a left side view thereof;

FIG. 6, is an isometric view thereof;

FIG. 7, is another isometric view thereof;

FIG. 8 is another isometric view thereof; and,

FIG. 9 shows the panel strip bracket in a condition of use, and an additional panel strip bracket in broken lines as showing environmental subject matter.

The broken lines in the drawings illustrate portions of the article, the additional broken lines shown in FIG. 9 illustrate environmental structure; all broken lines form no part of the claimed design.
